UNITED STATES PATENT OFFICE

LEO J. GRUBMAN, OF BELLE HARBOR, NEW YORK

EYE MOUNTING FOR DOLLS

Application filed February 7, 1927. Serial No. 166,370.

This invention relates to eye mountings for dolls, and has for its primary object to provide a mounting for oscillatory eye settings which is of exceedingly simple construction and may be very easily and quickly attached in positively fixed relation to the doll head wall to properly support the oscillatory eye members with relation to the respective eye openings therein without necessitating the exercise of a high degree of skill on the part of the workman.

The present invention comprehends certain improvements in such eye mountings, several examples of which are disclosed in my pending application for patent filed December 9, 1926, Serial No. 153,485. In these prior disclosures, the supporting member for the eye setting is provided with means which automatically becomes imbedded in the structure of the doll head wall upon imparting a relative movement to said member and the doll head in a lengthwise direction to thereby permanently fix said supporting member in its applied position. The invention forming the subject matter of this application in its broader aspects may be distinguished from my former invention, in that in the present case, the attaching means carried by the supporting member is caused to automatically imbed itself in the wall of the doll head by a relative rocking movement between the doll head and the supporting member about the centers of the hemispherical eye members. Thus in this case as in my former invention, the points at which the attaching parts will engage the doll head wall are definitely located by contact between the surfaces of the eye members and the walls of the eye sockets.

It is a more particular object of my present improvements to simplify the form and construction of the metal stamping from which the supporting member for the eye setting is produced and to provide the same with means which will insure adequate security in the attachment of said member to the structure of the doll head so that said member will be held in rigidly fixed relation to the head wall against possibility of shifting movement in any direction.

With the above and other objects in view, the invention consists in the improved eye mounting for dolls, and in the form, construction and relative arrangement of its several parts as will be hereinafter more fully described, illustrated in the accompanying drawings, and subsequently incorporated in the subjoined claims.

In the drawings, wherein I have illustrated one simple and practical embodiment of the invention, and in which similar characters designate corresponding parts throughout the several views,—

Figure 1 is a longitudinal sectional view through the front portion of a doll head showing one form of the supporting member for the eye setting in its attached relation to the head wall and showing the doll head in dotted lines in its initial position prior to the relative rocking movement between said head and the supporting member whereby the latter is permanently attached to the wall of the doll head;

Fig. 2 is a rear elevation showing the mounting and eye setting arranged upon the front wall of the doll head;

Fig. 3 is a horizontal sectional view taken on the line 3—3 of Fig. 1;

Fig. 4 is a similar view showing the supporting member prior to its attachment to the wall structure, and

Fig. 5 is a plan view of the sheet metal blank from which the supporting member is formed.

In the drawings, I have shown the front section of a doll head 5, said head being molded in the usual manner from wood pulp, papier-mâché or other composition material. The front wall of the doll head above the eye openings therein is formed with an internal projection or enlargement 6, and said enlargement is centrally provided with a vertically extending channel or recess 7 therein, said channel being continued below said enlargement and between the spaced eye openings as indicated at 8. At each of the eye openings in the wall of the doll head, the inner surface of the head wall is milled out to provide the concave sockets as indicated at 9.

The mounting or supporting member for the oscillatory eye setting in the embodiment thereof selected for purposes of illustration is formed from the stamped sheet metal blank illustrated in Fig. 5 of the drawings, said blank having a central body portion 9 and the side portions 10 which are bent along the lines indicated at 11 to provide side flanges extending at right angles to the plane of said body portion 9. At longitudinally spaced points this blank is cut or slit as shown at 12, said slits extending horizontally from points adjacent the center of the body plate 9 and into the side portions 10 to provide the pairs of resiliently yieldable tongues 13 and 14 respectively, it being noted from reference to Fig. 4 of the drawings, that after the side portions 10 of the blank are bent as stated to provide the parallel side flanges, the tongues 14 in their normal positions are disposed in the plane of the body part 9 of said blank and the free ends thereof project beyond the outer side faces of the parts 10. Each of the side parts 10 of the blank is further provided in one end thereof with a rectangular notch or recess 15 and intermediate of its ends with a bayonet slot 16. These notches 15 and slot 16 are adapted to receive parts on a suitably formed supporting arm (not shown) whereby the mounting may be held in a fixed position during the operation of effecting the attachment thereof to the wall of the doll head as will be later described.

Each side part 10 of the supporting member is further provided in one end thereof and in spaced relation to the bayonet slot 16 with a horizontally elongated opening 17 for the purpose of receiving the shaft or axis of the eye setting. At the opposite end of the supporting member, the body part 9 thereof is centrally provided with a longitudinally projecting spur 18 which is adapted to be bent inwardly to project at right angles to the plane of the body part 9 and between the two side parts 10 of the supporting member.

After the blank has been bent to the proper form as above described and as illustrated in Figs. 1 and 4 of the drawings, the eye setting is then associated therewith. This eye setting in the form herein illustrated consists of a shaft or axis 19 preferably of general rectangular form and upon each end of this shaft, the hemispherical eye members 20 are snugly fitted so that they are held against a relative rotating movement about the axis of said shaft. This shaft 19 is provided with cylindrically turned portions indicated at 21 which are engaged in the respective slots 17 of the supporting member for free turning or rotative movement. To the intermediate part of the shaft 19 the upper angularly bent end of a

resilient wire rod 22 is suitably fixed, said rod having an upper terminal portion indicated at 23 projecting rearwardly from the shaft 19 and which is adapted by contact with the body part 9 of the supporting member, to constitute a stop, limiting the rocking or oscillating motion of the hemispherical eye members to their closed positions. The lower end of the resilient rod 22 is adapted to contact with the neck wall of the doll head as shown in Fig. 1 to limit the rocking movement of the eye members to their open positions. Upon said rod intermediate of its ends a weight 24 of suitable size and form is fixed.

In the attachment of the eye mounting to the wall of the doll head, the mounting may be arranged either in a vertical or in a horizontal position upon a suitable tool arm, and the said tool arm with the mounting thereon is then positioned through the neck of the doll head and the walls of the eye sockets 8 are engaged upon the surfaces of the hemispherical eye members 20 while the doll head is held with relation to the mounting in substantially the obliquely inclined position indicated in dotted lines in Fig. 1 of the drawings. Preferably, the eye setting is so positioned on the mounting that the pupils on the surfaces of the eye members are visible through the openings in the head wall while the head is held in this position. The head is now bodily rocked upon the eye members, the part of the front wall above the eye openings moving towards the eye mounting. As said wall approaches the mounting, the projecting ends of the tongues 13 and 14 are first engaged by the side edges of the channel or recess 7 so that said tongues will be flexed or sprung rearwardly out of the plane of the body part 9 of the supporting member. The rocking movement is continued until the angular spur 18 on the upper end of the supporting member impales the head wall at the upper end of the recess 7. The tongues 13 and 14 owing to their tendency to return to their normal positions will deeply bite at their free ends into the structure of the head wall at the opposite sides of the recess 7. Since these tongues are provided at vertically spaced points at each side of the mounting, it will be evident that said mounting is thus securely locked in rigidly fixed relation to the wall structure against any possibility of a rearward or inward movement relative thereto, while said tongues in conjunction with the angular spur 18 also effectively secure said mounting against any possibility of vertical or longitudinal movement relative to the head wall. The side flanges of the member 9 cooperating with the side walls of recess 7 prevent lateral displacement of said member.

During the above described operation of attaching the supporting member to the wall

of the doll head, the cylindrical parts 21 of the shaft or axis of the eye setting are pressed forwardly by a suitably formed part on the tool arm into the forward ends of the elongated openings 7. Therefore, it will be understood that when the head with the attached mounting and eye setting are removed from the tool arm, the shaft or axis may have an angular shifting movement in these openings with respect to the supporting member and the wall of the doll head.

As will be observed from reference to Fig. 1 of the drawings, the lower extension 7' of the recess 7 gradually increases in depth, and the base wall of said recess diverges downwardly from the opposed front surface of the body part 9 of the supporting member. This allows for a variation in the depth of the eye receiving cavities 8 in different doll heads while insuring the proper relative spacing between the eye members and the sockets in the doll head in the oscillatory movement of the setting. It will further be noted that when the doll head is in the upright position shown in Fig. 1, after the mounting has been attached, the said mounting is disposed at a vertical inclination rearwardly from its upper end with respect to the general plane of the front wall of the doll head. Thus the longer axes of the elongated holes 17 are likewise positioned at a horizontal inclination so that the shaft 19 of the eye setting gravitates downwardly and forwardly therein, thereby maintaining a close contacting relation between the peripheral surfaces of the eye members 20 and the walls of the sockets or cavities 8. When however, the doll head is tilted or inclined to a definitely predetermined angle, the shaft 19 will move rearwardly by gravity in the opening 17, thus freeing the eye members from frictional contact with the walls of the sockets 8 and permitting of their un retarded oscillating motion to the closed position.

From the foregoing description considered in connection with the accompanying drawings, the construction, manner of use and several advantages of my improved eye mounting will be clearly and fully understood. While I have above referred to the supporting member as being first mounted in fixed relation to a stationary tool arm, it will be understood that a reversal of the above described operations may be carried out; or in other words, the doll head may be secured in a fixed position with the eye members of the setting engaged in the sockets 8, and the supporting member may then be swung or rocked about the axis of the eye members so as to cause its several attaching parts to become impaled or imbedded in the structure of the head wall in the manner above explained. In either case, it will be apparent that the attachment of

the supporting member to the wall of the doll head and in proper relation to the spaced eye openings may be very easily and quickly effected and that the proper relation of the eye members with respect to the openings in the doll head wall is also obtained with a free rocking or oscillating motion of said eye members, without necessitating the special skill heretofore required in this art in order to obtain the desired results. Likewise, it will be appreciated that the supporting member for the eye setting which consists of a single sheet metal stamping of very simple form can be produced at very small manufacturing cost. As this new mounting embodies no additional relatively movable parts for its attachment to the wall of a doll head or for retaining the eye setting in cooperative connection therewith, there is no possibility of the eye setting becoming bodily displaced from its proper operative relation with the openings in the head wall so that in the ordinary usage of the article to which the device is applied, the occasion will never arise where it is necessary to open the head for the purpose of repairing or replacing parts of the eye mounting.

I have herein shown a very desirable and practical embodiment of my present improvements. Nevertheless, it is to be understood that the essential features thereof might also possibly be attained in other alternative structural embodiments of the device. Accordingly, the privilege is reserved of resorting to all such legitimate changes in the form, construction and relative arrangement of the detail parts as may be fairly considered within the spirit and scope of the invention as claimed.

I claim:

1. As an improved article of manufacture, a supporting member for oscillatory eye settings consisting of a stamped sheet metal blank bent to provide an intermediate body wall and opposite side flanges and said side flanges at one of their ends having means to retain an eye setting in operative relation to a doll head wall, and resiliently yieldable anchoring means integral with the intermediate body wall of said member, having free ends intersecting the planes of said flanges and projecting beyond the outer faces of the side flanges for engagement with spaced surfaces on the wall structure of the doll head.

2. As an improved article of manufacture, a member having means for retaining an oscillatory eye setting in operative relation to a doll head wall, said member consisting of a metal plate adapted for insertion into an internal recess in the head wall and provided with resiliently yieldable parts adapted to cooperate with the opposite side walls of the recess when the plate is inserted.

therein to flex said parts out of the plane of said plate and place the same under tension whereby said parts are caused to interlock with the side walls of said recess and fix the plate therein against displacement relative to the head wall.

3. In combination with a doll head having spaced eye receiving cavities in its front wall and said wall being internally formed with spaced surfaces extending in predetermined angular relation to a common plane intersecting the centers of said cavities, a member positioned between said spaced surfaces having means for retaining an oscillatory eye setting in operative relation to said cavities and said member carrying laterally projecting, resiliently yieldable attaching parts embedded in said surfaces and automatically placed under tension by co-operation with said spaced surfaces as said member is moved to its applied position between said surfaces whereby said parts are caused to interlock with the structure of the head wall and prevent displacement of said member relative to said spaced surfaces.

20 4. In combination with a doll head having spaced eye receiving cavities in its front wall and said wall being internally formed with spaced surfaces extending in predetermined angular relation to a common plane intersecting the centers of said cavities, a plate having means at one end to retain an oscillatory eye setting in operative relation to said cavities, the other end of said plate extending between said spaced surfaces and having laterally projecting, resiliently yieldable parts cooperating with said spaced surfaces as the plate is moved to its applied position whereby said parts are flexed inwardly out of the plane of said plate and caused to interlock with the structure of the head wall whereby said plate is fixedly secured against displacement relative to said surfaces.

45 5. In combination with a doll head having spaced eye receiving sockets in its front wall and spaced vertically extending surfaces thereon between said sockets, a supporting member having bearing means at one of its ends for the axis of an oscillatory eye setting, the other end of said supporting member being positioned between said spaced surfaces on the head wall and provided with means embedded in the wall structure to anchor said member in fixed relation to the wall.

60 6. In combination with a doll head having spaced eye receiving cavities in its front wall and an internal recess centrally formed in said wall above the eye receiving cavities, an elongated supporting member having bearing means at one of its ends for the axis of an oscillatory eye setting, the other end of said member extending into said recess and being provided with laterally pro-

jecting resiliently yieldable anchoring means embedded in the opposite side walls of said recess.

7. In combination with a doll head having spaced eye receiving cavities in its front wall and an internal vertically extending recess above the eye receiving cavities, an elongated supporting member of channel shaped form in cross section, the side flanges of said member having bearing means at one of their ends for the axis of an oscillatory eye setting, said member extending at its other end into said recess in substantially parallel relation with the front wall of the doll head and being provided with resiliently yieldable anchoring parts projecting laterally beyond the side flanges of said member and embedded in the spaced vertical surfaces of said recess.

8. In combination with a doll head having spaced eye receiving cavities in its front wall and an internal vertically extending recess above the eye receiving cavities, an elongated supporting member of channel shaped form in cross section, the side flanges of said member having bearing means at one of their ends for the axis of an oscillatory eye setting, said member extending at its other end into said recess in substantially parallel relation with the front wall of the doll head and being provided with resiliently yieldable anchoring parts projecting laterally beyond the side flanges of said member and embedded in the spaced vertical surfaces of said recess, and an angularly projecting prong on the latter end of said member impaled in the base wall of said recess.

9. In combination with a doll head having spaced eye receiving cavities in its front wall and an internal vertical recess above said cavities, an oscillatory eye setting having an axis and spaced eye members thereon engaged in said cavities, and a supporting member for the eye setting formed from a one piece sheet metal blank having bearing means at one of its ends for the axis of the eye setting and extending in substantially parallel relation to the front wall of the doll head and into said recess, said member being provided with integrally formed parts embedded in the side and base walls of said recess.

10. In combination with a doll head having spaced eye receiving cavities in its front wall and an internal vertical recess above said cavities, an oscillatory eye setting having an axis and spaced eye members thereon engaged in said cavities, and a supporting member for the eye setting formed from a one piece sheet metal blank having bearing means at one of its ends for the axis of the eye setting and extending in substantially parallel relation to the front wall of the doll head and into said recess, said member having longitudinally spaced, resiliently

yieldable parts embedded in the opposite side walls of said recess.

11. In combination with a doll head having spaced eye receiving cavities in its front wall and an internal vertical recess above said cavities, an oscillatory eye setting having an axis and spaced eye members thereon engaged in said cavities, and a supporting member for the eye setting formed from a one piece sheet metal blank having bearing means at one of its ends for the axis of the eye setting and extending in substantially parallel relation to the front wall of the doll head and into said recess, said member having longitudinally spaced resiliently yieldable parts embedded in the opposite side walls of said recess, and the other end of said member having an integrally formed angularly projecting prong embedded in the base wall of said recess.

20 In testimony that I claim the foregoing as my invention, I have signed my name hereto.

LEO J. GRUBMAN.
